UNITED STATES PATENT OFFICE.

WILLIAM A. HOLGATE, OF DULUTH, MINNESOTA.

COMBINED CASE AND CIGAR-TIP CUTTER.

SPECIFICATION forming part of Letters Patent No. 599,707, dated March 1, 1898.

Application filed March 10, 1897. Serial No. 626,866. (No model.)

To all whom it may concern:

Be it known that I, WILLIAM A. HOLGATE, a citizen of the United States, residing at Duluth, in the county of St. Louis and State 5 of Minnesota, have invented certain new and useful Improvements in a Combined Case and Cigar-Tip Cutter; and I do hereby declare the following to be a full, clear, and exact description of the invention, such as will enable others skilled in the art to which it appertains to make and use the same.

My invention relates to improvements in match-boxes and cigar-cases, and particularly to that class of match-boxes and cigar-cases 15 which in addition to carrying matches and cigars are provided with means for clipping the tips of cigars.

It consists in the combination, with a suitable casing, of a plate adapted to be inserted 20 in said casing, so as to form a compartment within the same for holding matches, and a separate compartment carrying mechanism for clipping the ends of cigars and means connected with the cover for operating said 25 cigar-cutting mechanism.

It also consists in certain other novel constructions, combinations, and arrangements of parts, as will be hereinafter fully described and claimed.

30 In the drawings, Figure 1 represents a vertical section through the match-box, revealing the cigar-tip-clipping mechanism. Fig. 2 is a perspective view of the plate carrying the clipping mechanism, the same being removed from the match-box. Fig. 3 represents a vertical sectional view through the match-compartment, the cover of the box being thrown back and parts of the clipping mechanism shown in dotted lines. Fig. 4 represents a transverse vertical section through the match-box, and Fig. 5 represents a top plan view of the match-box with the cover thrown back.

In the drawings, A represents a suitable 45 casing, preferably constructed of metal and having its upper end closed by a hinged cover A', connected thereto by a hinge a at the rear edge of the casing. The cigar-tip clipping mechanism is mounted upon a plate B, adapt-

ed to fit in the casing A, the said plate also 50 serving to separate a match-compartment from the compartment occupied by the clipping mechanism. The plate B is preferably provided with side flanges b b and a top flange b', which extends nearly the full width of the 55 plate, but leaving at one end an opening through which the knife-operating means secured to the cover is adapted to extend, as will be hereinafter more fully described. Pivoted to the plate B is the knife-lever b², 60 provided with an angular arm b³ at its upper end and a knife-edge b⁴ at its lower end. As shown in Fig. 1, the lever b² may be actuated by a flat spring b⁵, secured at its upper end to a stud upon the plate B and held against 65 the lever b² by another stud or pin b⁶. As shown in Fig. 2, the flat spring may be dispensed with and a coil-spring b⁷ may be used to actuate the lever b² without departing from the spirit of my invention. The movement 70 of the lever b² is limited in one direction by a stud b⁸, mounted on the plate B. The plate B is provided at its lower end with a pendent extension carrying a spring-plate b⁹, which is provided with a catch or engaging lug b¹⁰. 75 The catch b¹⁰ is adapted to engage a projection b¹¹ upon the lower end of the knife-lever to hold it in its set position, as illustrated in Fig. 1. Opposite the end of the spring-plate b⁹ a perforation or hole a' is formed in the 80 casing.

When it is desired to clip the end of a cigar, it is only necessary to insert it in the aperture a' sufficiently far to force the spring-plate b⁹ inwardly. This releases the projection b¹¹ from the catch b¹⁰, and the spring is free to force the knife-lever to its farthest extremity. The knife-blade travels across the aperture a' and cuts off the inserted end of the cigar, and the aperture a' is formed in the casing immediately beneath the aperture a' in the side, so that the cigar-clippings may fall out of the casing and prevent the same from becoming clogged. In order to set the knife-lever again, it is only necessary to close the 90 match-box, when the lever b² will be forced backward to its set position by mechanism upon the said cover. This mechanism con-

sists of a spring-arm a^4 , riveted to the inside of the cover and carrying a dog a^5 upon its free end. When the cover A' is closed, the dog a^5 extends into the compartment occupied by the cigar-tip-clipping mechanism, its lower end engaging the projection b^3 upon the knife-lever b^2 and forcing it inward until the said lever is caught by the catch b^{10} . In order not to disturb the set of the lever in opening the box, the dog a^5 is provided with a bevel edge, as a^6 , so that when the cover is thrown open the dog will be sprung to one side and not move the lever b^2 . The match-compartment is preferably formed between the plate B and one side of the casing. The lower boundary of this compartment is preferably formed by a flat spring C, which also extends upwardly at each end to the top of the casing A, the end c being bent rearwardly, so as to exert a constant pressure upon the cover when closed, so as to force the same open when it is released. The other end, c' , is bent forward to form a catch to engage a corresponding catch a^7 upon the cover for holding it in its closed position. The spring C is also provided near one end with a stud c^2 , projecting through the casing, by which the catch c' may be forced inwardly in order to release the cover when it is desired to take a match from the box.

It will be apparent from the above description that my box might be readily adapted for carrying cigars instead of matches, it being merely necessary to make it upon a little larger scale. By my simple construction I am enabled to produce a compact and effective combined match-box and cigar-tip clipper which can be easily carried about in the pocket and is ready for use at any time.

Having now described my invention, what I claim as new, and desire to secure by Letters Patent, is—

1. In a match-box, the combination with a suitable box having a hole to receive the tips of cigars, of a plate therein forming a compartment for holding the matches, in one side of said box and a separate compartment for carrying mechanism for clipping the tips of cigars in the other side, means connected with the cover for setting the cigar-tip-clipping mechanism, the construction being such that the said tip-clipping mechanism is adapted to be tripped by the insertion of the tip of a cigar, substantially as described.

2. In a match-box, the combination with a suitable casing having a hole to receive the tip of a cigar, of a plate or partition mounted therein and dividing the said casing into two compartments, mechanism in one of said compartments for clipping the tips of cigars, means in the other compartment for controlling the cover of the match-box, the construction of the said tip-clipping mechanism being such that it is adapted to be tripped by the insertion of the tip of a cigar, substantially as described.

3. In a match-box, the combination with a casing having an opening to receive the tip of a cigar and another opening for the discharge of clippings, of a plate mounted in said casing, a knife-lever pivotally mounted on said plate, a spring for actuating the same, means for setting the knife-lever, means for holding it in the set position, and a cover for said box, the construction and arrangement being such that the said knife-lever is adapted to be tripped by the insertion of the tip of a cigar and the tip thereby clipped off, and reset upon closing the cover, substantially as described.

4. In a match or other box, the combination of an outer casing for holding matches or cigars, said casing being provided with an opening for the insertion of a tip of a cigar and also an opening for the discharge of clippings, a knife-lever pivot in said casing which is provided with engaging means, a horizontally-moving spring-plate carrying an engaging catch or lug and arranged back of and in line with the opening provided for the insertion of the tip of a cigar, said catch being adapted to engage the lower end of the knife-lever and hold it in a set position, and a cover on said box provided with means for setting the knife-lever, substantially as described.

5. A match-box having a hole to receive the tip of a cigar, a knife-lever pivotally mounted therein, a spring for actuating the same, a cover hinged to said casing, and a spring-dog secured to said cover adapted to engage the upper end of the knife-lever whereby the same is adapted to be set upon closing the cover and means for securing the knife in its set position, substantially as described.

6. In a match-box the combination with a casing provided with a hole to receive the tips of cigars, of a knife-lever pivotally mounted thereon, a spring for actuating the same, a cover hinged to the said casing, a setting means mounted in said cover consisting of a spring secured to the cover at one end, the other end of said spring being free and carrying a dog, said dog being adapted to extend into the casing when the cover is closed and engage the upper end of knife-lever for setting the same, and retaining means for securing the knife-lever in its set position, substantially as described.

7. In a match-box the combination with a casing provided with a hole to receive the tips of cigars, of a knife-lever pivotally mounted thereon, a spring for actuating the same, a cover hinged to said casing, a setting means secured to said cover consisting of a spring carrying a dog at its free end, said dog being provided with a beveled edge whereby the lever may be set upon closing of the lever but will not be disturbed upon the opening thereof, and means for holding the knife-lever in its set position, substantially as described.

8. A match-box having a cover and provided with mechanism for clipping the tips of ci-

gars, and means connected with the cover for setting the cigar-tip-clipping mechanism, the construction and arrangement of the parts being such that the cover can be raised and lowered without the clipping mechanism being operated except to set the same, substantially as described.

In testimony whereof I affix my signature in presence of two witnesses.

WILLIAM A. HOLGATE.
